UNITED STATES PATENT OFFICE.

ALONZO HEBBARD, OF NEW YORK, N. Y., ASSIGNOR TO DOMINICK & HAFF,
OF SAME PLACE.

DESIGN FOR A HANDLE FOR A SPOON OR FORK.

SPECIFICATION forming part of Design No. 12,888, dated April 18, 1882.

Application filed February 28, 1882. Term of patent 7 years.

To all whom it may concern:

Be it known that I, ALONZO HEBBARD, of the city, county, and State of New York, have invented a new and Improved Design for the 5 Handles of Spoons, Forks, or other Articles, of which the following is a full, clear, and exact description.

Reference is to be had to the accompanying drawings, forming a part of this specification, 10 in which similar letters of reference indicate corresponding parts in all the figures.

Figure 1 is a plan view of my improved design shown as applied to a spoon - handle. Figs. 2 and 3 are sectional elevations of the 15 same, taken respectively through the lines *x x* and *y y*, Fig. 1.

My design consists in the straight inwardly-inclined side edges and the flat forward side having the inner part of its side edges beveled, and also in the angular outer end in connection with the straight inwardly-inclined side edges and the flat forward side having the inner part of its side edges beveled, as will be hereinafter fully described.

25 A represents a handle, the side edges, B, of which are straight and incline toward each

other from the outer end of the handle to, or nearly to, its inner end. The outer end, C, of the handle A is made angular, as shown in Fig. 1. The forward side of the outer part of the 30 handle A, for about half the length of the said handle, is made flat, as shown in Figs. 1 and 3. The forward side of the inner part of the handle A is beveled along its edges, as shown in Figs. 1 and 2.

Having thus described my invention, I claim as new and desire to secure by Letters Patent—

1. The design for a handle herein shown and described, the same consisting of the straight inwardly-inclined side edges and the 40 flat forward side having the inner part of its side edges beveled, as set forth.

2. The design for a handle herein shown and described, the same consisting of the straight inwardly-inclined side edges, the angular outer end, and the flat forward side having the inner part of its side edges beveled, as set forth.

ALONZO HEBBARD.
